MAURICE HAUTOT, OF PARIS, FRANCE, ASSIGNOR TO COMPAGNIE INTERNATIONALE DES WAGON-LITS ET DES GRANDS EXPRESS EUROPEENS, OF PARIS, FRANCE, A COMPANY OF FRANCE

RAILWAY CARRIAGE

Application filed June 26, 1928, Serial No. 288,400, and in France December 6, 1927.

This invention relates to the construction of railway carriages, and more particularly sleeping carriages.

The construction according to the present invention is characterized by a partitioning arrangement and various constructional elements of such a nature that, in addition to a comfortable arrangement, a particularly strong construction is obtained, capable of resisting destructive shocks.

The above and other features of novelty will be apparent from the following description of preferred embodiments illustrated in the accompanying drawings, in which:—

15 Fig. 1 is a diagrammatical plan view showing the partitioning arrangement in a carriage according to the invention. This figure, which shows only a part of the carriage, represents four compartments forming two pairs, the remaining portion of the carriage being divided into like compartments.

Fig. 2 is a plan view and a part horizontal section on a larger scale, showing in greater detail the construction of a pair of compartments adapted to inter-communicate.

Fig. 3 is a longitudinal section of Figure 2.

Fig. 4 is a perspective view obtained by section and removal passing approximately through the centre of a compartment.

30 Fig. 5 is a perspective view showing a modified embodiment of the framework.

Fig. 6 is a perspective view showing the arrangement of the lavatory, in open position.

Figs. 7 and 8 are two plan views showing 35 a modified door for the lavatory.

In these various figures, the lateral walls of the carriage are indicated by 1 and 2, the roof is indicated by 3, and the partition separating the compartments from the corridor 40 is indicated at 4.

The two adjacent compartments are indicated at A and B, the corridor at C and the two lavatories at D and E.

The two compartments A and B of each 45 pair are separated by a partition 5, 5' of special form, whilst the partitions 7 between the pairs of compartments are perpendicular to the side walls of the carriage, in the usual way.

50 The specially shaped partition comprises

an oblique centre portion 5, whilst its ends 5'—5' straighten out to connect up on the one hand with the wall 2 of the carriage and on the other hand with the partition 4 of the corridor in such a manner that the whole of the partitions 5'—5—5' resembles the form of a very open S.

The substantially triangular spaces formed between the partition 5'—5—5' and the wall 2 on the one hand and the partition 4 on the other hand, constitute the two lavatories, of which the one D belongs to the compartment A and the other to the compartment B.

These lavatories D and E may be isolated from their respective compartments by 65 means of doors having two leaves 8—8.

This arrangement presents the advantage that, when the traveller, desiring to use the lavatory, has opened the two leaves 8—8 of the door, the latter are applied, on the one hand against the partition 5 and on the other hand against the partition 4 or wall 2 (see Fig. 6).

These surfaces which, in a carriage de luxe are covered with decorative facings of a somewhat delicate nature, are thus, owing to the two opened leaves 8—8, fully protected against any splashes due to the use of the lavatory and the latter thus represents a location utilizable as a dressing room which would in reality be considerably larger than the space which it actually occupies.

In addition the partition 5'—5—5' is connected at the top to the walls 2 and 4 by the lintels 8' of the above mentioned doors 8—8 and from the floor up to a certain height by the casing 15 of the lavatory, which is rigidly fixed to these walls (Fig. 6).

The partition 5'—5—5' may be provided at 5 with a door 6 to permit communication between the two compartments A and B of a pair.

The partition 5'—5—5' is erected approximately only up to the level of the plane at which the roof 3 joins the vertical walls 2 and 4, and at this level the partition 5'—5—5' is connected to two wide channel plates 9—9 which extend on the one hand across the compartment A and on the other hand into the compartment B, their ends being fixed to the 100

wall 2 of the carriage and to the partition 4 of the corridor.

The two plates 9—9 which serve as baggage racks are connected along their plane 5 of juxtaposition perpendicular to the walls 2 and 4 to a vertical plate 10 which is itself perpendicular to these walls 2 and 4 and which rises to the roof 3 to which it is connected.

It should be remarked that the two horizontal plates 9—9 together with the vertical plate 10 constitute respectively the flanges and web of a T-iron structure of large dimensions which thus forms part of the framework of the carriage and braces the 15 walls 2 and 4 in a rigid manner and connects them to the roof 3. The plates 9—9 may naturally be replaced by gratings, punched plates and the like, which likewise form a T-iron structure with the vertical plate 10 20 and which simultaneously serve as baggage racks fixed to the partition 5'—5—5' and to the lavatory compartments D and E.

Besides, if it is assumed that the flanges 9—9 of the T-iron structure are integral with 25 the partition 5'—5—5' and the two lavatories D and E and that the latter form a kind of hollow column having a large cross section it will be seen that the structure of the whole is extremely rigid and that the partition 4 of the corridor is fixed in the particularly rigid manner by the structure 9—10—9 of T-shape which maintains the absolute parallelism of the said partition 4 30 with the one wall of the carriage and even, in the modified embodiment hereinafter described (Fig. 5), with the two walls. The solidity of the whole of the carriage, relatively to the usual construction of railway carriages, is thus increased to a great degree.

40 In the embodiment shown in Figs. 1 to 4, the vertical plate 10 forming the flange of the T-structure terminates at one side against the partition 4 of the corridor, but it may, if desired, be prolonged by means of a part 10' 45 as far as the other side wall 1 of the carriage, as shown in Fig. 5, in such a manner that the two walls 1 and 2, are, as previously stated, very strongly braced by the series of members 9—10—10'—9 stretching throughout 50 the width of the carriage.

The windows illuminating the compartment are indicated at 11, the windows of the lavatories at 12 and the beds at 13; the doors 55 communicating with the corridor are indicated at 14.

It will thus be seen that this entity, whilst effecting an increase in the rigidity of the whole construction, renders it possible to provide, for each compartment, a lavatory adapted to open and ensure the maximum of comfort.

The fittings as also the furnishings details 60 may, however, comprise certain modifications without the essential characteristics of

the construction being thereby modified. Thus for example, the lavatory may, instead of comprising the two-leaved door 8—8 shown in Figs. 1 to 6, be constructed with a single leaf door, as shown in Figs. 7 and 8, 70 which represent an arrangement of this description in plan view. In this case, the single leaf door 16 is provided with a rod 17 hingedly mounted and supporting a curtain 18. When the door is closed (Fig. 7) 75 the rod 17 is folded back against the inner face of the door, and when the latter is open (Fig. 8) the rod is brought into a position at right angles to the door so that a temporarily enlarged closed lavatory is obtained 80 shut off from the rest of the compartment.

What I claim is:

1. In a railway compartment including lateral walls and a roof, and S-shaped partition subdividing said compartment into two 85 chambers, the central part of said partition forming an angle with the transverse axis of the vehicle, said compartment being characterized in that said partition is connected with two horizontal plates forming baggage racks and connected with a vertical plate extending to the roof, the assemblage of these horizontal and vertical plates forming a T-member which braces the lateral walls of the compartment and assures perfect rigidity of 90 the entire vehicle and the parallelism of the passage partition with said lateral walls.

2. Compartment as claimed in claim 1, characterized in that the vertical plate forming the wing of the T-member is extended 100 beyond the passage partition to the other wall of the vehicle, so as to brace both walls of the passage partition.

3. Compartment as claimed in claim 1 and including a toilet in which the walls defining 105 the toilet and angularly arranged with respect to each other connect the said partition in such manner as to define, together with the lateral walls of the compartment, hollow triangular columns integral with the rest of 110 the construction, thus increasing the rigidity of the whole.

In testimony whereof I have signed my name to this specification.

MAURICE HAUTOT.
